UNITED STATES PATENT OFFICE.

FRANK J. HERRICK, OF NEW BRITAIN, CONNECTICUT.

DESIGN FOR A COMBINATION-TOOL.

SPECIFICATION forming part of Design No. 19,913, dated June 17, 1890.

Application filed December 20, 1889. Serial No. 334,452. Term of patent 7 years.

To all whom it may concern:

Be it known that I, FRANK J. HERRICK, of New Britain, Hartford county, in the State of Connecticut, have invented and produced a new and useful original Design for a Combination Implement for Shop and Household Use, whereof the following is a specification.

My new and useful design is delineated in the annexed drawing, which shows an outline 10 on the implement, wherein the head thereof, containing various members, as hammer, hoof-pick, and wrench, is formed to indicate the features of horn, head, mouth, and beard of a horned animal's head.

15 A, the handle, is formed of two bars *b b*, placed side by side and united at the ends, forming a space between them, the outline of which is that of an elongated ovoid *c*. At one end of the ovoid the handle has a short 20 extension, whose outline is the frustum of a

cone *d*, and this is the screw-driver of the implement. At the other end of the handle the configuration of the various members forming the head of the tool is contrived to develop the outline of an animal's head, as of 25 a he goat. The horn portion *e*, whose outline is that of one limb of a crescent, forms the pick of the implement. The notch *f*, representing the mouth, forms the wrench, and the rectangular outline *g*, answering to the beard, 30 indicates the part used as a hammer. Thus the design presents the semblance of a horned animal's head.

I claim—

The design for a combination-tool, as herein 35 shown and described.

FRANK J. HERRICK.
